UNITED STATES PATENT OFFICE.

GEORGE E. BISHOP, OF CLEVELAND, OHIO.

AUTOMOBILE INCLOSURE.

Application filed February 4, 1924. Serial No. 690,440.

My invention relates to automobile side inclosures and particularly to non-folding door panels for car bodies having permanent tops. The objects of this invention are to provide in the permanent top type such an arrangement of the panel supporting and bracing elements as to make it unnecessary to raise the panel against the top, when it is desired to remove the same from the door. Thus the panel can be readily removed from, and replaced upon, the door even though there is very little space at the top rail because of the rigid construction. Further detailed improvements will be disclosed by the accompanying drawing and completely described in the following description.

The annexed drawing and the following description set forth in detail certain means embodying my invention, such disclosed means constituting, however, but a few of the various forms in which the principle of the invention may be applied.

In said annexed drawing:

Figure 1 is a fragmentary side elevation of a car body including a door upon which is mounted one of my improved panel constructions;

Figure 2 is a fragmentary transverse vertical section, taken in the plane indicated by the line II—II, Figure 1;

Figure 3 represents a vertical section and elevation, taken in the plane indicated by the line III—III, Figure 1;

Figure 4 represents an elevation of a plate or bracket attached to the automobile door and to which is detachably secured a panel brace hereinafter described;

Figure 5 is an elevation of the lower end of said brace;

Figure 6 is a transverse horizontal section, upon an enlarged scale, taken in the plane indicated by the line VI—VI, Figure 1;

Figures 7, 8 and 9 represent, respectively, a plan view of a special type of door bushing; an elevation of said bushing; and a perspective of the lower end of a supporting rod adapted to cooperate with said bushing; and

Figures 10, 11 and 12 represent, respectively, a fragmentary transverse vertical section of a vehicle door to which is secured a special two-part brace cooperating with a special bushing member; an elevation of said two-part brace; and a vertical section of said special bushing member.

Referring to the annexed drawing in which the same elements are indicated by the

same respective ordinals in the several views, I indicate an automobile body by the ordinal 1, a door therefor by the ordinal 2, an automobile top by the ordinal 3 and a door panel 158 adapted to ride in and out with the door and removable from the door, as occasion requires, by the ordinal 158. This door panel 158 is adapted to cover the body opening between the door 2 and the top 3 but, because of the rigid top rail 8 adjacently below which the upper horizontal edge of the panel 158 lies, this panel 158 cannot be materially moved in a vertical plane. Thus, the panel supporting rod cannot be lifted out of its usual door bushing. However, it is often desired to remove the panel 158 from the door 2. Therefore, I have provided an improved construction which will allow for this removal and replacement of the panel 158 and the detail of this construction is as follows:

The panel body comprises a built-up wood frame 16—17 having an outer sheet metal cover 15 suitably secured to the built-up wood body member and extending exteriorly of said body member to form a suitable lapping edge, as plainly shown in Figure 6. Interiorly of the wood frame the sheet metal section 15 extends a suitable distance to form a sheet metal bead 20 upon which, when suitably covered by fabricoid or lining, or both, the outer face of a glass outlook 7 rests. This glass outlook 7 is retained upon the inner face by means hereinafter fully described. The combination wood and sheet metal frame is exteriorly covered by a suitable weatherproof cover such as fabricoid 22 which extends from the lapping edge forwardly over the sheet metal bead 20 and is secured to the inner lateral edge of the wood frame. The interior of the panel 158 is lined with any suitable lining and to the outer edges of the fabricoid 22 and this inner lining is stitched a suitable binding indicated by the ordinal 24.

Referring to the left-hand side of the panel 158 shown in Figures 1 and 3, it will be noted that I provide a brace 142 which is pivoted upon a pin 143 seated in a plate 170 secured to the wood frame 16—17 by screws 144. Secured to the inner face of the door 2 by screws 150 and adjacent the upper edge of said door is a plate 149 formed with a stud-head 151 adapted to be seated in a hole 148 formed in the lower section 146 of the brace 142. I secure the brace section

146' to the door 2 by means of a cap screw 152 which passes through a hole 147 in the brace section 146' and into the plate 149.

Referring particularly to the rod end side of the panel shown in Figures 1 and 6, it will be noted that there has been secured to the wood frame 16-17 an additional vertical sheet metal section 106 by means of nails 107, said section 106 extending outwardly of the frame member and being turned to form a channel 108 adapted to receive the upper cylindrical section of a substantially vertical supporting rod 165 having a lower end offset 166 formed with a non-cylindrical door bushing receiving portion 166' adapted to fit the cooperating door bushing 71. In order that I may provide a stop for the upper end of the supporting rod 165, I pass a screw 83 under the sheet metal member 15 of the panel 158 and adjacent the upper edge of the rod 165, as plainly shown in Figure 1.

From the foregoing description it is evident that when it is desired to remove the panel 158 from the door 2, the latter can be opened enough to allow easy access to the screw 152 and that upon the removal of the latter, the brace 142 can be lifted off from the pin 151 and thus freed from the door 2. Thus the panel 158 can be swung in horizontal planes upon the rod 165 so as to free the hinge side of the panel from the rigid top rail 8 and when the door is opened enough to swing the handle edge of the door out beyond the edge of said top rail, then the whole panel is freed and can be lifted from the door with the offset rod 165. I wish particularly to direct attention to the pivotal connection of the brace 142 with the panel body. This pivotal connection provides a joint at the top and bottom of the panel with the canopy and door 2, respectively, which is weatherproof and yet flexible enough to force the panel to make said joints with a tension which is just adequate for the purpose desired, allowing also for easy and satisfactory opening and closing of the door 2 with the panel 158 mounted thereon.

Referring particularly to Figures 7, 8 and 9, I have therein disclosed a bushing 45 adapted to be secured to the inner face of the door 2 and formed with a vertical rectangular rod-receiving slot 46 which is adapted to receive the flat rectangular end 48 of a rod 47, the latter being securely held in the bushing 45 by means of a pin 49 adapted to intersect the hole 50 formed in the bushing 45 and to be seated in the rod section 48. This form of bushing will serve the purpose performed by the bushing 71 shown in Figure 1.

Referring particularly to Figures 10, 11 and 12, I show therein a substitute construction for the brace construction 142. This

substitute construction consists of a two-part brace section adapted to be secured to the inner face of the door 2. The lower section 132 of the brace is secured by means of screws 133 to the door 2 and is formed with an upper exteriorly-threaded portion 135 adapted to cooperate with an interiorly-threaded bushing 136. A second brace section 137 is formed with an enlarged lower head 138 of a diameter too large to pass through a hole 139 formed in the upper part of the bushing 136. It is evident that the bushing 136 can be dropped over the brace section 137 until the head 138 of the latter is caught in the hole 139 of the bushing 136 and then the latter turned upon the threaded portion 135 of the brace section 132 until the desired tension is obtained.

What I claim is:

1. The combination with a vehicle body including a door and a top having a rigid top rail; of a removable side inclosure comprising a rigid panel adapted to cover the door heading between the top and the door, supporting means for mounting said panel upon the vehicle door so as to ride in and out with the latter, said supporting means including a brace upon the hinge side securing together the panel and door and detachably connected to at least one of them, and a substantially vertical panel supporting rod non-rotatably secured to the door upon the handle side, the panel being adapted to be turned on said rod, whereby, the brace being detached from the door or panel, the latter can be swung outwardly from the body and horizontally around said rod to enable, when the door is open, the lifting of the panel from the door without interference with the rigid top rail.

2. The combination with a vehicle body including a door and a top having a rigid top rail; of a removable side inclosure comprising a rigid panel adapted to cover the door heading between the top and the door, supporting means for mounting said panel upon the vehicle door so as to ride in and out with the latter, said supporting means including a brace secured to the panel body and detachably secured to the door upon the hinge side, and a substantially vertical panel supporting rod non-rotatably secured to the door upon the handle side, the panel being adapted to be turned on said rod, whereby, the brace being detached from the door, the panel can be swung outwardly from the body and horizontally around said rod to enable, when the door is open, the lifting of the panel from the door without interference with the rigid top rail.

3. The combination with a vehicle body including a door and a top having a rigid top rail; of a removable side inclosure comprising a rigid panel adapted to cover the door heading between the top and the door,

supporting means for mounting said panel upon the vehicle door so as to ride in and out with the latter, said supporting means including a brace pivotally secured to the panel body and detachably secured to the door upon the hinge side, and a panel supporting rod non-rotatably secured to the door upon the handle side, the panel being adapted to be turned on said rod, whereby, 5 the brace being detached from the door, the panel can be swung outwardly from the body and horizontally around said rod to enable, when the door is open, the lifting of the panel from the door without interference with the rigid top rail.

4. The combination with a vehicle body including a top having a rigid top rail; of a removable side inclosure comprising a rigid panel adapted to cover the door heading between the top and the door, supporting means for mounting said panel upon the vehicle door so as to ride in and out with the latter, said supporting means including a brace upon the hinge side securing together 20 the panel and door and detachably connected to at least one of them, means secured vertically along the panel edge upon the handle side and forming a cylindrical channel, a rectangular bushing secured to the door upon the handle side, a rectangular supporting rod seated in said bushing and having a cylindrical upwardly extending section contained in said cylindrical channel, whereby, the brace being detached from the door or 25 panel, the latter can be swung outwardly from the body and horizontally around said rod to enable, when the door is open, the lifting of the panel from the door without interference with the rigid top rail.

40 5. The combination with a vehicle body including a door and a top having a rigid top rail; of a removable side inclosure comprising a rigid panel adapted to cover the door heading between the top and the door, supporting means for mounting said panel

upon the vehicle door so as to ride in and out with the latter, said supporting means including a brace secured to the panel body and detachably secured to the door upon the hinge side, a cylindrical sheet metal channel secured vertically along the panel edge upon the handle side, a rectangular bushing secured to the door upon the handle side, a rectangular supporting rod seated in said bushing and having a cylindrical upwardly extending section contained in said cylindrical channel, whereby, the brace being detached from the door, the panel can be swung outwardly from the body and horizontally around said rod to enable, when 50 the door is open, the lifting of the panel from the door without interference with the rigid top rail.

6. The combination with a vehicle body including a door and a top having a rigid top rail; of a removable side inclosure comprising a rigid panel adapted to cover the door heading between the top and the door, supporting means for mounting said panel upon the vehicle door so as to ride in and out with the latter, said supporting means including a brace pivotally secured to the panel body and detachably secured to the door upon the hinge side, a cylindrical sheet metal channel secured vertically along the 65 panel edge upon the handle side, a rectangular bushing secured to the door upon the handle side, a rectangular supporting rod seated in said bushing and having a cylindrical upwardly-extending section contained in said cylindrical channel, whereby, the brace being detached from the door, the panel can be swung outwardly from the body and horizontally around said rod to enable, when the door is open, the lifting of the panel from the door without interference with the rigid top rail.

Signed by me this 28th day of January, 1924.

GEORGE E. BISHOP.
